PROCESS OF PREPARING AMINO-COMPOUNDS OF THE STEROID SERIES

Josef Schmidt-Thomé, Frankfurt am Main Unterliederbach, Germany, assignor to Farbwerke Hoechst Aktiengesellschaft vormals Meister Lucius und Brüning, Frankfurt am Main-Hochst, Germany, a German company

No Drawing. Application March 22, 1952, Serial No. 278,132. In Germany March 30, 1951.

6 Claims. (Cl. 260—397.5)

1

The present invention relates to the manufacture of compounds having the character of the male sexual hormones.

In my application Ser. No. 278,131, filed March 22, 1952 and entitled "Process of Preparing Amino-Compounds of the Steroid Series" is described a process for the manufacture of 17-acetyl-amino-compounds of the cyclopentano-polyhydrophenanthrene series by subjecting 20-oximes of the said series to the Beckmann re-arrangement with the aid of phosphorus oxychloride and pyridine.

An object of the present invention is to provide a process for the hydrolysis of 17-acetyl-amino-compounds of the cyclopentano-polyhydrophenanthrene series so as to obtain the corresponding 17-amines.

In U. S. specification No. 2,212,363 is described a process for making amines of the cyclopentano-polyhydrophenanthrene series in which compounds of the said series containing in the 17-position the group

are subjected to the Beckmann re-arrangement. The re-arrangement is brought about by treating the oxime with thionyl chloride in solution in benzene. There are also mentioned as re-arrangement agents phosphorus pentachloride and sulfuric acid. The 17-acetyl-amino-compounds so obtained are not isolated, but are converted directly into the 17-amines by hydrolysis with strong acids. The yields of the amines amount to about 30 per cent.

The small yields of the amines are probably due mainly to the fact that the steroids are not resistant to strong acids during long reaction periods and at high temperatures, and that side reactions may occur during hydrolysis in an acid medium.

In U. S. specification No. 2,531,441 it is stated that it is not possible in practice to hydrolyze 17-acetyl-amino-compounds. This statement does not conflict with the statements in the specification No. 2,212,363, since the acid hydrolysis described therein is not suitable for use on an industrial scale owing to the long duration of the heating, and, as stated above, side reactions occur. In Example 19 of the aforesaid U. S. specification the paratoluene sulfonate of 3β -acetoxy- Δ^5 -pregnene-20-one-oxime, after re-arrangement with dilute sulfuric acid and being already partially hydrolyzed in 3-position, is treated with a solution of potassium hydroxide in methanol,

2

whereby hydrolysis in the 3-position alone is completed. The 17-acetyl group is not attacked. Even during the subsequent heating of the compound with ethanolamine, a strongly basic substance, no hydrolysis occurs in the 17-position, and the unaltered starting material is recovered.

The present invention is based on the observation that 17-acetyl-amino-compounds of the cyclopentano-polyhydrophenanthrene series, which contain a hydroxyl or acetylated hydroxyl group as a substituent in the 3-position, can be hydrolysed very readily with inorganic alkaline substances at a temperature above 95° C. The free 17-amines are obtained from the 17-acetyl amines in a yield exceeding 90 per cent.

The hydrolysis of the 17-acetyl amines with inorganic alkaline substances may be carried out either in solvents boiling above 95° C., advantageously monohydric or polyhydric alcohols, such as n-butyl alcohol, amyl alcohol, isoamyl alcohol, ethylene glycol, propylene glycol, glycerin or the like, or organic bases, such as ethanolamine, quinoline or the like. Alternatively, the hydrolysis may be carried out in an autoclave with the addition of a monohydric or polyhydric alcohol, such as methyl, ethyl, propyl, isopropyl, butyl, isobutyl, amyl or isoamyl alcohol, ethylene glycol, propylene glycol or glycerin, or an organic base, such as ethanolamine, pyridine, quinoline or the like as a solvent.

The hydrolysis takes place at temperatures above 95° C., advantageously at a temperature above 160° C. Suitable inorganic alkaline substances are alkaline earth hydroxides, alkali carbonates and above all alkali hydroxides. They are advantageously used in a concentration of 15 to 20 per cent. If, for example, an alcoholic solution of sodium hydroxide of 20 per cent. strength is used in a closed vessel at a temperature of 160° C.—180° C., and the duration of the heating is 3 hours, the free 17-amine is obtained from 17-acetylamine in a yield exceeding 90 per cent. The same yield is obtained by boiling for 2 hours in a solution of 15 per cent. strength of potassium hydroxide in ethylene glycol.

The free 17-amines may be prepared as such and isolated. As, however, they are sometimes obtained in an oily form, it is of advantage to isolate them in the form of their salts. This may be carried out, for example, by adding an ethereal solution of an acid to an ethereal solution of the amine. The amine salt then precipitates. Organic or inorganic acids may be used for the precipitation, for example, acetic acid, oxalic acid, succinic acid, benzoic acid, phthalic acid, sulfuric

3

acid, hydrochloric acid, perchloric acid or the like.

The free amines can easily be recovered from the salts by mixing the latter in an alcoholic solution with alkali and pouring the mixture into water. The amine, which separates, can then be isolated by filtration and washed with water or extracted with ether.

The compounds of the invention are useful as medicaments or as intermediate products for the preparation of medicaments.

The following examples serve to illustrate the invention but they are not intended to limit it thereto:

Example 1

700 milligrams of 3β -acetoxy-17-acetylaminoo- Δ^5 -androstene are suspended in 20 cc. of alcohol, a solution of 3 grams of sodium hydroxide in 10 cc. of water is added, and the mixture is heated for 4 hours at 180° C. in a closed copper tube or in a V2-steel tube. The reaction solution is poured into water, the product is extracted with ether, and the ethereal solution is washed with water, dried and concentrated by evaporation. When a small portion of glacial acetic acid is added, the acetate of 3β -hydroxy-17-amino- Δ^5 -androstene precipitates. The yield amounts to 620 milligrams (95 per cent. of the theoretical yield) and the product melts at 227-230° C. (uncorrected). The product may be recrystallized from a mixture of alcohol and ethyl acetate, and is then obtained in the form of fine needles. Instead of sodium hydroxide, the corresponding quantity of potassium hydroxide may be used equally well. Instead of ethyl alcohol, there may be used methyl, propyl or isopropyl alcohol or a polyhydric alcohol, such as ethylene glycol or glycerin. An organic base, such as pyridine, ethanolamine or the like, may also be used as solvent, in which case the reaction temperature and the period of reaction must, if required, be increased.

The free hydroxy-amine base can be obtained from the salt or directly from the hydrolysis solution as follows:

1 gram of the acetate of 3β -hydroxy-17-amino- Δ^5 -androstene is suspended in methanol. By the addition of a few drops of caustic soda solution complete dissolution is brought about. The solution is then poured into water. The precipitate which is initially finely flocculent can be readily filtered after being allowed to stand for a short time. After drying on the water-bath, 860 milligrams of crude 3β -hydroxy-17-amino- Δ^5 -androstene (95 per cent. of the theoretical yield) are obtained. The product is recrystallized from dilute methanol in the form of laminae melting at 162° C. (uncorrected).

The free amine may be isolated directly in the hydrolysis, as follows:

2 grams of 3β -acetoxy-17-acetylaminoo- Δ^5 -androstene are hydrolyzed as described above in a closed steel tube. The reaction solution is poured into water, and the reaction product which separates in the form of flocks is filtered off and thoroughly washed with water. 1.45 grams of crude 3β -hydroxy-17-amino- Δ^5 -androstene are obtained. The product melts at 162° C. (uncorrected). The yield amounts to 91 per cent. of the theoretical yield.

The crude compound may be purified as follows:

500 milligrams of crude 3β -hydroxy-17-amino-

4

Δ^5 -androstene are dissolved in 5 cc. of alcohol, and 0.2 cc. of freshly distilled benzaldehyde are added. After a few seconds crystals begin to separate. After 10 minutes the crystals are separated by filtration. 550 milligrams of the benzal compound are obtained melting at 232° C. After recrystallization from butyl acetate the product melts at 234° C. (uncorrected).

The benzal compound may be split again as follows:

200 milligrams of the benzalamine so obtained are suspended in 5 cc. of alcohol and 0.5 cc. of concentrated hydrochloric acid is added, whereupon dissolution occurs at once. The mixture is boiled for 10 minutes and lamellae of 3β -hydroxy-17-amino- Δ^5 -androstene hydrochloride separate. After cooling, the hydrochloride is filtered off. To convert it into the free amine it is suspended in a small quantity of methanol and a few drops of sodium hydroxide solution are added. The crystals of the hydrochloride dissolve, and then 3β -hydroxy-17-amino- Δ^5 -androstene crystallizes. The product is identified by the mixed melting point method.

Example 2

1 gram of 3β -hydroxy-17-acetylaminoo- Δ^5 -androstene is heated in a mixture of 30 cc. of alcohol and 3 grams of sodium hydroxide (dissolved in 5 cc. of water) in a closed tube for 4 hours at 160-180° C. The reaction solution is then poured into water, extracted with ether and the ethereal solution is washed with water, dried and concentrated to about 100 cc. On adding a small quantity of a solution of oxalic acid in ether, the oxalate of 3β -hydroxy-17-amino- Δ^5 -androstene precipitates.

Example 3

40 250 milligrams of 3β -acetoxy-17-acetylaminoo-androstan in a mixture of 10 cc. of alcohol and 1.25 g. of sodium hydroxide (dissolved in 2.5 cc. of water) are heated for 2 hours in a closed copper tube at 180° C. The reaction solution is poured into water and the white precipitate which separates is filtered off with suction, washed with water and dried. 180 milligrams of 3β -hydroxy-17-amino-androstan are obtained melting at 150° C. The yield amounts to 95 per cent. of the theoretical yield. As the product recrystallizes sparingly from methanol, it is dissolved in ether, and the ethereal solution, after being dried, is concentrated by evaporation and mixed with a few drops of glacial acetic acid. The acetic acid salt which precipitates at once melts at 217° C. (uncorrected). After repeated recrystallization from a mixture of methanol and ethyl acetate, the pure acetate of 3β -hydroxy-17-aminoandrostan is obtained in the form of lamellar crystals which melt at 228° C. (uncorrected).

Example 4

1.8 grams of 3β -acetoxy-17-acetylaminoo- Δ^5 -androstene are heated at the boil for 3 hours under reflux in 100 cc. of glycol together with 15 grams of potassium hydroxide. The solution is then poured into water and extracted with ether. The ethereal solution is washed with water, dried with sodium sulfate, concentrated to about 100 cc. and gradually mixed with acetic acid. 1.5 grams of the acetate of 3β -hydroxy-17-amino- Δ^5 -androstene precipitate. It melts at 227° C. (uncorrected). Instead of the potassium hydroxide there may be used the corresponding quantity of sodium hydroxide. Instead of glycol, there may

be used propylene glycol or glycerin. An organic base of high boiling point, such as ethanolamine, quinoline or the like may also be used as solvent.

Example 5

500 milligrams of 3β -hydroxy-17-acetylamino- Δ^5 -androstene are heated at the boil for 2 hours in a reflux apparatus in a solution of 5 grams of potassium hydroxide in 30 cc. of ethylene glycol. A small content of water is not detrimental, but the boiling point of the solvent mixture must be higher than 180° C. The reaction mixture is poured into water, the precipitate, which separates in the form of flocks, is filtered off and washed with water. After recrystallization from methanol, 370 milligrams (85 per cent. of the theoretical yield) of 3β -hydroxy-17-amino- Δ^5 -androstene are obtained; the product melts at 160° C. (uncorrected). It is not essential to carry out the hydrolysis at the boiling temperature. Thus, the hydrolysis may be conducted at a temperature below the boiling point, but then the period of the reaction is correspondingly increased. Thus, for example, heating for 4½ hours at 180° C. is necessary.

The acetylamine may also be hydrolyzed with sodium hydroxide or potassium hydroxide in butanol, but in this case the period required for the reaction is substantially increased.

I claim:

1. The process of producing amino compounds of the steroid series which comprises hydrolyzing 17-acetylamino compounds of the formula

wherein R is a cyclopantanopolyhydrophenanthrene radical, which is substituted in position 3 by a member of the group consisting of hydroxyl and acylated hydroxyl by means of an inorganic, strong alkaline substance at a temperature above 95° C.

40

2. The process according to claim 1, which comprises hydrolyzing 17-acetylamino compounds of the formula

wherein R is a cyclopantanopolyhydrophenanthrene radical, which is substituted in position 3 by a member of the group consisting of hydroxyl and acylated hydroxyl by means of an inorganic, strong alkaline substance at a temperature above 95° C. and at an elevated pressure.

3. The process according to claim 1, which comprises hydrolyzing 17-acetylamino compounds of the formula

wherein R is a cyclopantanopolyhydrophenanthrene radical, which is substituted in position 3 by a member of the group consisting of hydroxyl and acylated hydroxyl by means of an inorganic, strong alkaline substance at a temperature above 95° C. and at atmospheric pressure.

4. The process according to claim 1, which comprises hydrolyzing 3β -acetoxy-17-acetylamino-androstene by means of an inorganic, strong alkaline substance at a temperature above 95° C.

5. The process according to claim 1, which comprises hydrolyzing 3β -hydroxy-17-acetylamino-androstene by means of an inorganic, strong alkaline substance at a temperature above 95° C.

6. The process according to claim 1, which comprises hydrolyzing 3β -acetoxy-17-acetylamino-androstan by means of an inorganic, strong alkaline substance at a temperature above 95° C.

JOSEF SCHMIDT-THOMÉ.
